UNITED STATES PATENT OFFICE.

ROBERT M. ROBINSON, OF LOUISVILLE, KENTUCKY, ASSIGNOR TO CHEATHAM ELECTRIC SWITCHING DEVICE CO., INC., OF LOUISVILLE, KENTUCKY, A CORPORATION OF KENTUCKY.

AUTOMATIC TROLLEY SWITCH.

Application filed December 22, 1923. Serial No. 682,236.

The object of my invention is to provide an automatic switch of this character which will be simple in construction and reliable in operation and not disturbed by cars too close together or by a car standing under a trolley pan and in which all circuits carrying an arcing current will be broken away from the trolley pan and where a magnetic extinguisher will extinguish the arc so that all danger of burning the apparatus from this cause is obviated.

This and other objects are accomplished by my invention, one embodiment of which is hereinafter more particularly set forth.

For a more particular description of my invention, reference is to be had to the accompanying drawings, forming a part hereof, in which

Figure 1 shows a system embodying my improvements.

Figure 2 shows an instrument box with various instruments used in this system.

Throughout the various views of the drawings, similar reference characters designate similar parts.

As is usual in switches of the character in question, commonly known as Cheatham switches, the bar 14 of the trolley pan 1 has a wire 18 that runs to a controlling relay magnet 19 and this magnet has a second wire 20 which runs to the trolley wire so that when a trolley wheel 21 is connecting the bars 14 and 15 and off the trolley wire, any current which the car motors use must pass through the relay magnet 19. The bar 15 will then derive this current from this magnet, and through the bar 14 and current from the bar 15 may reach the ground through a wire 22, armature 23 of a slow release relay 24, wire 25, magnet 26 of a blow out relay, wire 27, resistance 28, wire 29 to ground 30. The bar 15 has two curved ends 13 which function in the separation of the trolley wheel from the trolley wire. The magnet 24 has two coils, one with the usual ohmic resistance of say five hundred or six hundred ohms and another coil 24^a preferably on a second core, has a very small resistance say one turn of large copper, short circuited on itself so that when a current is cut off from flowing through the coil of greater resistance, there will be a reaction in the coil of low resistance which will prolong the magnetic action of the core and make it hold its magnet-

ism for a perceptible interval of time after the circuit through the magnet 24 is broken. 55

The coil 26 is the coil of a relay with two armatures 31 and 32, both of which are connected to a wire 33 that runs to the wire 20 which is connected to the trolley wire 2. Between the armatures 32 and 31 the wire 33 carries a resistance 34 of substantially forty-five ohms. The wire 33 also runs to an armature 35 below the armature 23 or adjacent thereto and also controlled by the magnet 24 and making a stick relay thereof. When this armature 35 is raised it engages a contact at the end of a wire 36 that runs to a wire 37 which runs to an unlocking contactor 38 adjacent to the trolley wire 2. From the ground 30 the wire 29 is connected to a wire 39 that runs to a resistance 40 and from thence a wire 41 runs immediately above the armature 32 and another wire 42, connected to the wire 41 runs to the magnet 24. Above the armature 32 is a second contact which is connected to a wire 75 43 that runs to the wire 22 which has been described above.

The armature 31 below the magnet 26 is preferably provided with a magnetic blow out 44 and the end of this armature, when 80 raised, engages a wire 45 that runs to a resistance 46 of about thirty ohms, more or less, and this resistance is connected by a wire 47 to an armature 48 which is immediately below the magnet 19 and controlled by the same. 85 The upper contact of the armature 48 is at the end of a wire 49 that runs to a holding up coil 50 which has a second wire 51 that runs to a ground solenoid 52 which has a ground wire 53 in the conventional manner. An adjacent ground solenoid 54 has the same ground wire 53 connected in the same manner and also a wire 55 that runs to the lower contact below the armature 48 and on which it normally rests. 95

An instrument box 56 of the conventional kind is preferably provided so as to protect the various instruments which can be protected in such a box.

In view of the foregoing, the operation of my improved switch system will be readily understood, the parts being assembled, as above described. When a trolley wheel reaches a trolley pan 1, while moving in the direction of the arrow, it leaves the wire and rests immediately thereafter on the sections 100 105

13 and 14 and then it leaves the section 13 and bridges between the sections 14 and 15 where it passes along until it passes again on to sections 14 and 13 at the other end of the 5 trolley pan and thence back to the wire. The trolley wheel 21 is on the trolley pan only a brief interval, depending on the speed of the car, unless some accident happens which causes the car to stop with the wheel on the 10 trolley pan. Assuming that the operation is normal and the trolley wheel 21 is in the position shown and that the track connections, not shown, are as usual, if the motorman applies power to his car so as to energize the relay 15 19 and thereby raise the armature 48. If he does not apply power to his car he will not raise this armature. On the assumption that he does apply power to his car, the circuits will now be traced. First there is a circuit 20 through the magnet 19 of the relay from the trolley wire through the wire 20, magnet 19 and wire 18 to bar 14 and thence through the wheel 21 to the ground and a shunt circuit will go through the bar 15, wire 22, armature 25 23, (which is normally up) wire 25, coil 26, wire 27, resistance 28 to the ground thereby energizing the blow out relay 26 and raising its two armatures to close contacts at 32, 43 and 45. As soon as this is done the coil 24 30 is short circuited because current passes to the ground from the trolley wires through the wire 20, solenoid 19, wire 18, bar 14, trolley wheel 21, bar 15, wire 22, wire 43, armature 32, wire 41, resistance 40, wire 39, and 35 wire 29 to ground 30, and so it is deenergized but does not immediately become deenergized because of the short circuited coil 24^a and the dropping of the armature 23 and 35 is slightly delayed, say for half a second.

40 During the brief interval after the magnet 24 is short circuited and before it is deenergized entirely and while it holds its armatures 23 and 35, the magnet 26 remains energized through the wire 22, above mentioned, 45 armature 23, wire 25, wire 27, resistance 28, and wire 29 to ground and while so energized a current can pass through armature 31 from the trolley wire 2 to the armature 48, as above pointed out, so that the ground magnet 52 50 will be energized when the armature 48 is raised. When raised the magnet 50 is energized and so this armature 48 will be held up as long as a current passes through it although the magnet 19 may be deenergized 55 by the trolley wheel 21 leaving the trolley pan 1. During this interval the ground solenoid 52 has time to act and does act to shift the rail, not shown. The circuits remain closed but an instant, depending on the time 60 element of the coil 24^a and then the armatures 23 and 35 fall and open the circuit through the magnet 26 and its armatures 31 and 32 fall and open all circuits depending on them including the circuit through the armature 65 48. These remain open until the wheel 21

connects the bar 38 with the wire 2 and then a circuit is closed through the wire 37, magnet 24, wire 42, resistance 40, wire 39 and wire 29 to ground 30 and then this magnet 24 is energized and it raises its armatures 23 70 and 35 to their normal positions and closes the circuits depending on these armatures and not open elsewhere and particularly a circuit through the wire 13, wire 33, armature 35, wire 36, wire 37, magnet 24 and through 75 the wire 42 to ground 30, as above described, thereby again energizing the magnet 24.

If a car passes with power off the motors, the operation is the same as above described, except that the magnet 19 is not enough energized to raise the armature 48 so that no circuit is closed through the wire 49, but a circuit is closed through the wire 55, in due season so that the solenoid 54 is made active and functions accordingly. 80

In view of the foregoing, it will be readily understood that the magnet 24^a is so designed that the armatures 23 and 35 are held long enough after the deenergizing of the magnet 24 to enable the ground solenoid 52 or the ground solenoid 54 to function properly so that no matter how rapidly a trolley wheel may traverse the trolley pan, the apparatus will have time to function properly and it is also apparent that once the apparatus has 90 functioned, as above set forth, and the trolley wheel has not reached the contactor 38, the apparatus cannot be made to operate and will remain inoperative until the contact between the wheel and part 38 again energize the magnet 24 so that no car can be derailed by a 95 following car when using this switching device. 100

It will be noted that after the relay 26 is energized a stick circuit is set up direct from the trolley wire 2 through the wire 20, wire 33, armature 32, wire 43, armature 23, wire 25, relay 26, wire 27, resistance 28 and wire 29 to the ground. 105

While I have shown and described one embodiment of my invention, it is obvious that it is not restricted thereto, but that it is broad enough to cover all structures that come within the scope of the annexed claims. 110

Having thus described my invention, what I claim is:

1. In a system of the class described a pair of ground solenoids, a trolley wire, a trolley pan, a controlling relay connected to said trolley pan determining which of the ground solenoids shall be energized, a normally energized slow release relay, a third relay with a magnet in circuit with an armature of the second mentioned relay, a line contactor connected to said slow release relay for use in restoring the apparatus after operation, said third relay controlling said slow release relay and operating circuits for the ground solenoids controlled by said third relay. 120

2. In an electric switch operating device a 130

- pair of solenoids, a source of power, a trolley pan, a slow release stick relay normally energized from said source and means for operating said solenoids including a relay connected 5 to said trolley pan and means controlled by said slow release relay to energize said relay.
3. In an electric switch operating device, a pair of solenoids, a source of power, a trolley pan, a slow release relay normally energized 10 from said source, means for operating said solenoids including a relay connected to said trolley pan and means controlled by said slow release relay to energize said relay, means for shunting said slow release relay to prevent 15 further operation of switch and means including an auxiliary contact and an energizing circuit for said slow release relay adapted to be closed upon contact of a collector with said auxiliary contact for restoring the apparatus after operation.
4. In an electric switch operating system a pair of solenoids, a source of power, a trolley pan, a slow release stick relay connected normally to the source of power, means including a relay connected to said trolley pan controlled by said slow release relay for directing current through the said solenoids and means for deenergizing said slow release relay in order to prevent operation of the 25 switch during the time said slow release stick relay is deenergized.
5. In an electric switch operating device, a pair of solenoids, a source of power, a trolley pan, a slow release relay connected normally 30 to the source of power, means including a relay connected to said trolley pan controlled by said slow release relay for directing current through the said solenoids, means for deenergizing said slow release relay in order 35 to prevent subsequent operation of the switch and means including an auxiliary contact and energizing circuit for said slow release relay adapted to be closed upon contact of a collector with said auxiliary contact for restoring the energization of said slow release relay.
6. In an electric switch operating device, a pair of solenoids for operating a switch, a source of power, a trolley pan, a relay connected to said pan, a normally energized slow 40 release stick relay connected to said source of power, operating circuits to said solenoids controlled by said slow release relay and said first relay and means for automatically deenergizing said slow release stick relay in order 45 to prevent further operation of said switch operating device during the passage of a car.
7. In an electric switch operating device, a pair of solenoids for operating a switch, a source of power, a trolley pan, a relay connected to said pan, a normally energized slow 50 release relay connected to said source of power, operating circuits to said solenoids including a relay energized by means controlled by said slow release relay and said first relay, and means for automatically deenergizing said 55
- slow release relay in order to prevent further operation of said switch operating device during the passage of a car, and means including an auxiliary contact for restoring the energization of said slow release relay after the passage of a car. 70
8. In an electric switch operating device, a pair of solenoids, a source of power, a trolley pan, a selecting relay connected to said trolley pan, a slow release stick relay connected normally to the source of power, means controlled by said slow release relay for directing current through the said solenoids comprising an auxiliary relay, means for deenergizing said slow release relay by said auxiliary relay and means for deenergizing said auxiliary relay after said slow release relay becomes deenergized. 75
9. In an electric switch operating device, a pair of solenoids, a source of power, a slow release stick relay connected normally to the source of power, means including a relay energized by means controlled by said slow release stick relay for directing current through the said solenoids, means for deenergizing said slow release stick relay in order to prevent subsequent operation of the switch and means for restoring the energization of said slow release relay. 80
10. In an electric switch operating system, a pair of solenoids, a source of power, a trolley pan, a slow release relay connected normally to the source of power, means including a relay connected to said trolley pan controlled by said slow release relay for directing current through the said solenoids, means for deenergizing said slow release relay in order to prevent operation of the switch during the time said slow release relay is deenergized, means for preventing subsequent energization of said slow release relay, and means including an auxiliary contact for restoring the system to normal. 95
11. In an electric switch operating device, a pair of solenoids, a source of power, a trolley pan, a selecting relay connected to said trolley pan, a slow release stick relay connected normally to the source of power, means controlled by said slow release relay for directing current through the said solenoids, an auxiliary relay connected to said trolley pan, means for deenergizing said slow release relay by said auxiliary relay, means for deenergizing said auxiliary relay after said slow release relay becomes deenergized, and means for restoring the energization of said slow release relay. 100
12. In an electric switch operating device, a pair of solenoids, a source of power, a trolley pan, a normally energized slow release stick relay, an auxiliary relay, an energizing circuit for said auxiliary relay connected to said trolley pan and controlled by said slow release relay and a stick circuit for said auxiliary relay shunting said trolley pan and 105
- means for automatically deenergizing said 110
- 130

means for operating said solenoids controlled by said auxiliary relay.

13. In an electric switch operating device, a pair of solenoids, a source of power, a trolley pan, means controlling said solenoids, an auxiliary relay, an energizing circuit for said auxiliary relay connected to said trolley pan and controlled by said controlling means and a circuit for said auxiliary relay shunting said trolley pan, means for operating said solenoids controlled by said auxiliary relay, an auxiliary contact and an energizing circuit for said controlling means adapted to be closed upon contact of a collector with said auxiliary contact.

14. In an electric switch operating device, the combination with the track solenoid, trolley conductor and trolley contactor, of a normally open circuit connecting the trolley conductor and track solenoid, a circuit closing means therein, and means controlled by contact of a trolley with the trolley contactor for operating the circuit closing means, a retarded release relay controlling said contact control means and adapted to be shunted by said contact controlled means permitting operation of said circuit closing means for a predetermined time whereby the controlling circuit of the circuit closing means will be held opened by said retarded release relay and

thereby rendering said circuit closing means inoperative against subsequent trolley contacts until the car has passed a certain predetermined restoring point.

15. In an electric switch operating device, the combination with the track solenoid, trolley conductor and trolley contactor, of a normally open circuit connecting the trolley conductor and track solenoid, a circuit closing means therein equipped with an operating coil, an auxiliary normally energized retarded release relay having two armatures and separate controlling contacts, one armature controlling the retarded release relay and one armature included in the circuit of said operating coil and means controlled by contact of a trolley with a trolley contactor for initially energizing the operating coil of the circuit closing means, and circuit means for said retarded release relay controlled by said operating coil to prolong the energization of said operating coil and deenergize the said normally energized retarded release relay thereby opening the circuit of said operating coil whereby the circuit closing means will be inoperative until the car has passed a certain predetermined restoring point.

In testimony whereof, I have hereunto set my hand this 6th day of November, 1923.

ROBERT M. ROBINSON.
